(57) **CLAIM**

The ornamental design for an electrophoresis buffer pad holder, as shown and described.

DESCRIPTION

FIG. 1 is a front perspective view of an electrophoresis buffer pad holder according to the design.

FIG. 2 is a front view thereof.

FIG. 3 is a bottom view thereof.

FIG. 4 is a top view thereof.

FIG. 5 is a back view thereof.

FIG. 6 is a right side view thereof.

FIG. 7 is a left side view thereof.

FIG. 8 is a back perspective view thereof; and,

FIG. 9 is a top perspective view thereof.
